UNITED STATES PATENT OFFICE

2,480,785

PRODUCTION OF SUGAR C-NITROALCOHOLS

John Clinton Sowden and Hermann Otto Laurenz Fischer, Toronto, Ontario, Canada, assignors to Corn Products Refining Company, New York, N. Y., a corporation of New Jersey

No Drawing. Application October 10, 1946,
Serial No. 702,370

11 Claims. (Cl. 260—333)

1

This invention relates to the production of carbohydrate C-nitroalcohols, a class of compounds in which the group

is incorporated in a sugar alcohol structure.

An object of the invention is to provide an improved method of producing carbohydrate C-nitroalcohols.

The first known member of this class of compounds was prepared by the action of alkali and nitromethane on an acetylated sugar cyanohydrin in methanol solution (Sowden and Fischer, J. Am. Chem. Soc., 66, 1312 (1944)). The main disadvantage of this method was that the sugar cyanohydrin employed in the reaction had to be synthesized by a series of reactions from a simple carbohydrate. Thus, the cyanohydrin upon which the successful practice of the previous method depended was an expensive and difficultly obtainable substance. Furthermore, the yield of sugar C-nitroalcohol obtained by such method was rather low.

The present method constitutes an improvement over the method previously described. In general, the improved method consists in effecting chemical reaction, in the presence of an alkaline reagent, between an aldose sugar and a nitroparaffin. At the conclusion of the reaction period, the desired product may be recovered by several techniques, hereinafter described.

The reaction of the present invention is believed to proceed according to the following illustrative equations:

Any aldose sugar, as well as any aldose sugar containing substituents which may impart thereto increased aldehyde activity, may be used for purposes of the present invention. Examples of such compounds include D- and L-arabinose, D- and L-xylose, D-ribose, D-glucose, 4,6-benzylidene-D-glucopyranose, 2,4-benzylidene-L-xylopyranose and the like.

Any nitroparaffin containing the group

$\begin{array}{c} | \\ -C\text{H}_2\text{NO}_2 \end{array}$

may be used for purposes of the present invention. Examples of such compounds include nitromethane, nitroethane, nitropropane, and the like.

Alkaline reagents which may be used include sodium metal in methanol, ethanol and the like; potassium hydroxide; and equivalents of such reagents. Alkali salts of substituted aldose sugars previously specified may also be used to provide the necessary carbohydrate reagent for the reaction.

One atom of sodium or potassium or equivalent alkaline material per molecular weight of aldose sugar or derivative thereof is sufficient to bring about a moderately rapid condensation reaction, whereas two atoms of sodium or potassium per mole of sugar give a much more rapid reaction without appreciably affecting the yield or product.

The reaction medium should be a mutual solvent for the reactants, and should be inert with respect to the desired reaction. Solvents such as methanol, ethanol and their equivalents may be used as the reaction media.

The progress of the reaction between aldose sugars and nitroparaffins may be ascertained conveniently by observing the change in optical rotation of the reaction mixture. When the rotation of the mixture has become substantially constant, the reaction is considered essentially complete.

Theoretically, one mole of nitroparaffin is required to react with each mole of sugar in accordance with the present invention. However, nitroparaffins tend to react with alkaline substances to produce undesirable by-products and hence not all of the nitroparaffin is available for reaction with the sugar. Also, the rate of the reaction is increased when more nitroparaffin than that theoretically required is used. Therefore, in carrying out the present invention, it is desirable and preferable to use a considerable excess of the nitroparaffin over that theoretically required. Any unreacted nitroparaffin may be recovered for reuse in subsequent reactions.

No external heating or cooling of the reaction mixture is necessary. At room temperature, i. e., about 22 to 28° C., the reaction goes essentially to completion in 24 hours or less when two moles of alkaline agent are used per mole of sugar. At temperatures lower than room temperature, the necessary time of reaction is longer although no appreciable difference in yield is apparent. Elevated temperatures are not desirable due to the resulting rapid disappearance of the nitroparaffins under the influence of alkali and the production of undesirable colored by-products. In general the temperature at which the reaction is effected should not exceed about 40° C.

Commercial or reagent grades of the reactants, the alkaline agents and the mutual solvents or reaction media heretofore mentioned are satisfactory for purposes of the present invention. However, they should all be in substantially anhydrous condition in order for the desired reaction to take place with the greatest degree of efficiency.

The carbohydrate C-nitroalcohols obtained by the condensation of unsubstituted aldoses and nitroparaffins may be isolated as the sodium salt, or as carbohydrate C-nitroalcohols themselves by removing the sodium from the salt. In some instances, the carbohydrate C-nitroalcohols are crystalline and in other instances, they are liquids or sirups.

The product obtained from the condensation reaction when a benzylidene derivative is used as one of the reactants is a benzylidene carbohydrate C-nitroalcohol. This may be converted to the unsubstituted sugar C-nitroalcohol by hydrolyzing off the benzylidene group with a dilute mineral acid, such as dilute sulfuric acid. This procedure has been described in J. Am. Chem. Soc., 66, 1312 (1944) and is not claimed as part of this invention.

Sugar C-nitroalcohols produced in accordance with the present invention will contain one more carbon atom than the sugars from which they are derived when the nitroparaffin used is nitromethane. The nitro group may be eliminated from the sugar C-nitroalcohol in each case by adding an alkali salt solution thereof to a moderately concentrated sulfuric acid solution to produce an aldehyde group. (J. Am. Chem. Soc.,

66, 1312 (1944)). The present invention, therefore, constitutes a means of lengthening a sugar chain. The properties of several sugar C-nitroalcohols are also described by Sowden and Fischer in the aforementioned publication and also in J. Am. Chem. Soc., 67, 1713 (1945) and ibid. 68, 1511 (1946).

Theoretically, two isomeric sugar C-nitroalcohols arise from any one aldose sugar used in the reaction with nitromethane. However, all the isomers possible of formation have not been isolated. Thus, where 4,6-benzylidene-D-glucopyranose was used as a reactant with nitromethane, 5,7-benzylidene-1-nitro-1-desoxy-D-alpha-glucopyranitol was isolated, but not the corresponding D-beta-glucopyranitol derivative.

When nitromethane and 4,6-benzylidene-D-glucopyranose were used as reactants, another type of nitroalcohol than heretofore described, e. g., 5,7-benzylidene-2,6-anhydro-1-nitro-1-desoxyglucopyranitol, was isolated. (See Example 15). This compound is not one of the isomers to be expected normally from the reaction. From this compound 2,6-anhydro-1-nitro-1-desoxyheptitol was prepared. (See Example 16.) The structure of 2,6-anhydro-1-nitro-1-desoxyheptitol is as follows:

The following examples which are intended as informative and typical only and not in a limiting sense will further illustrate the invention, which is intended to be limited only in accordance with the scope of the appended claims.

PREPARATION OF 1-NITRO-1-DESOXY-D-MANNITOL AND 1-NITRO-1-DESOXY-D-SORBITOL

Example 1

To a suspension of 50 grams of D-arabinose in 100 ml. of methanol and 180 ml. of nitromethane was added 10.5 g. of sodium in the form of sodium methoxide in 350 ml. of methanol. The sugar dissolved rapidly and an amorphous precipitate began to form a few minutes later. After the mixture was shaken for 18 hours at room temperature, the precipitate was separated therefrom by filtration and was washed with a mixture of equal parts of methanol and ethyl ether, then with ethyl ether and finally with petroleum ether. There was obtained 83 g. of dry material containing 9.1% of sodium by analysis.

This product was dissolved in 400 ml. of water and then was passed through a column of an ion exchange resin (sold under the trade name of AMBERLITE-I.R.-100-A. G. by Resinous Products Corporation) sufficient to remove the sodium ions. The resulting solution was concentrated at reduced pressure and allowed to crystallize. Fractional recrystallization of the crystals thus obtained from absolute ethanol yielded the following crystalline fractions:

- A 28.2 g. M. P. 124-129° C.
- B 8.3 g. M. P. 105-107° C.
- C 12.1 g. M. P. 95-135° C. (crude mixed nitroalcohols)

Fraction A, upon recrystallization from absolute ethanol, yielded pure 1-nitro-1-desoxy-D-manni-

tol, M. P. 133 to 134° C. (α)_D²⁵ in water (concentration 5.7 g. per 100 ml. of solution) was -6.8°.

Fraction B, upon recrystallization from absolute ethanol, yielded pure 1-nitro-1-desoxy-D-sorbitol, M. P. 108 to 109° C. (α)_D²⁵ in water (concentration 6.1 g. per 100 ml. of solution) was -9.7°.

PREPARATION OF 1-NITRO-1-DESOXY-L-MANNITOL AND 1-NITRO-1-DESOXY-L-SORBITOL

Example 2

When 25 g. of L-arabinose was treated in a manner similar to that described above for D-arabinose, the following products were obtained:

1-Nitro-1-desoxy-L-mannitol, M. P. 133 to 134° C. (α)_D²⁵ in water (concentration 6.2 g. per 100 ml. of solution) was +7.0°. The yield was 18.5%.

1-Nitro-1-desoxy-L-sorbitol, M. P. 108 to 109° C. (α)_D²⁵ in water (concentration 6.7 g. per 100 ml. of solution) was +9.5°. The yield was 18.8%.

PREPARATION OF 1-NITRO-1-DESOXY-D-GULITOL AND 1-NITRO-1-DESOXY-D-IDITOL

Example 3

When 10 g. of D-xylose was treated in a manner similar to that described above in Example 1, there was obtained 16.5 g. of a mixture of the amorphous sodium salts of 1-nitro-1-desoxy-D-gulitol and 1-nitro-1-desoxy-D-iditol, containing 9.1% of sodium. Removal of the sodium ion by means of a suitable ion exchange resin then gave the crude mixed nitroalcohols as a colorless sirup.

PREPARATION OF 6-NITRO-6-DESOXY-L-SORBITOL AND 6-NITRO-6-DESOXY-L-MANNITOL

Example 4

When 7 g. of L-xylose was treated similarly to the above examples, there was obtained 6.75 g. of a mixture of the sodium salts of 6-nitro-6-desoxy-L-sorbitol and 6-nitro-6-desoxy-L-mannitol, containing 9.0% of sodium. Removal of the sodium ion by means of a suitable ion exchange resin then gave the crude mixed nitroalcohols as a colorless sirup.

PREPARATION OF 1-NITRO-1-DESOXY-D-ALLITOL AND 1-NITRO-1-DESOXY-D-ALTRITOL

Example 5

When 10 g. of D-ribose was treated similarly to the above examples, there was obtained 14 g. of a mixture of the sodium salts of 1-nitro-1-desoxy-D-allitol and 1-nitro-1-desoxy-D-altritol, containing 9.3% of sodium. These were converted as in the above examples to the colorless, sirupy crude nitroalcohols.

PREPARATION OF 2,4-BENZYLIDENE-6-NITRO-6-DESOXY-D-SORBITOL

Example 6

2,4-benzylidene-L-xylopyranose was prepared from 2,4-benzylidene-D-sorbitol, according to the method described by V. Vargha (Ber. 68, 18, 1377 (1935)). 53.7 g. of this material in sirupy form was dissolved in a suitable glass container, in a mixture of 1 liter of absolute methanol and 160 ml. of nitromethane (reagent grade). To this was added 10 g. of sodium as sodium methoxide in 800 ml. of absolute methanol. The entire mixture was allowed to stand for 22 hours at room temperature after which 27 ml. of glacial acetic

acid was added thereto. The resultant mixture was then concentrated at reduced pressure. Some crystals formed during this operation and upon allowing the concentrated liquor to cool, more crystals formed. These crystals were purified by recrystallization once from water, a total of 34 g. (50%) being obtained. They were identified as 2,4-benzylidene-6-nitro-6-desoxy-D-sorbitol. The melting point thereof was 192 to 194° C. and (α)_D²² in water (concentration 1 g. per 100 ml. of solution) was -4.4°.

Example 7

When crystalline 2,4-benzylidene-L-xylopyranose (M. P. about 180° C.) was substituted for the sirupy material used in Example 1, a yield of 51% of the crude 2,4-benzylidene-6-nitro-6-desoxy-D-sorbitol was obtained.

PREPARATION OF 6-NITRO-6-DESOXY-D-SORBITOL FROM 2,4-BENZYLIDENE-6-NITRO-6-DESOXY-D-SORBITOL

Example 8

To 10 g. of 2,4-benzylidene-6-nitro-6-desoxy-D-sorbitol prepared according to Example 6 was added 100 ml. of 0.1 N sulfuric acid and the mixture was heated at 75 to 80° C. for 1 hour. The mixture was then cooled and the liberated benzaldehyde was removed by extraction with ether. Barium carbonate was added to neutralize the sulfuric acid and the barium sulfate which precipitated was removed by filtration. The clear solution remaining was evaporated, at reduced pressure, to dryness. The sirup remaining crystallized spontaneously after several days.

The crystals were recrystallized from a mixture consisting of ethyl acetate and a small amount of methanol. There was obtained 5.56 g. (79%) of 6-nitro-6-desoxy-D-sorbitol which showed a melting point of 78 to 80° C. When the 6-nitro-6-desoxy-D-sorbitol was crystallized several times either from dry ethyl acetate or from dry butanol, two types of crystals were obtained from such successive recrystallization from each solvent. The one type was in the form of fine needles melting at 81 to 83° C. and the other type was in the form of hard, compact prisms melting at 89 to 91° C. The two forms were interchangeable by appropriate conditions of concentration, rate of cooling or inoculation of their solutions and both showed (α)_D²⁴ in water (concentration 5 gr. per 100 ml. of solution) -7.9°. They were, therefore, dimorphic crystalline forms of the same substance. The proof of the structure and properties of 6-nitro-6-desoxy-D-sorbitol have been described by Sowden and Fischer (J. Am. Chem. Soc., 67, 1713 (1945)).

PREPARATION OF 5,7-BENZYLIDENE-1-NITRO-1-DESOXY-D-ALPHA-GLUCOHEPTITOL

Example 9

100 g. of 4,6-benzylidene-D-glucopyranose was dissolved, in a suitable glass container, in a mixture consisting of 1500 ml. of absolute methanol and 250 ml. of nitromethane (reagent grade) and to the resulting solution was added 1 liter of absolute methanol containing 17.3 g. of sodium as sodium methoxide. After standing for 8 hours at room temperature, the solution was acidified with 47 ml. of glacial acetic acid and was then concentrated at reduced pressure to a sirup. To the sirup was added 200 ml. of water. The resulting solution was concentrated at reduced pressure until all of the methanol and unreacted nitromethane had been removed. The resulting con-

centrated aqueous solution was cooled, whereupon a crystalline product formed. The crystalline product was separated by filtration and washed with ice water. There was obtained 25.9 g. (21%) of crude crystals which were identified as 5,7-benzylidene-1-nitro-1-desoxy-D-alpha-glucoheptitol. After this product was crystallized once from water and several times from a mixture consisting of equal parts of ethyl acetate and petroleum ether, it showed a melting point of 160 to 162° C. $(\alpha)_D^{28}$ from water (concentration 1.1 g. per 100 ml. of solution) was -42.5°.

Example 10

The crystalline sodium salt of 4,6-benzylidene-D-glucopyranose was prepared by the method of Zervas, Ber., 64, 2289 (1931). 114 g. of this salt, containing 1 mole of sodium per mole of sugar, was dissolved, in a suitable container, in a mixture of 315 ml. of nitromethane (reagent grade) and 2000 ml. of commercial synthetic methanol. The solution was allowed to stand at 10 to 12° C. for 187 hours. Thereafter, 25 ml. of glacial acetic acid was added to the solution and the entire resulting mixture then concentrated at reduced pressure to a sirup. The resulting sirup was dissolved in about 500 ml. of water and concentrated at reduced pressure to about 200 ml. The concentrated sirup was cooled, whereupon crystalline 5,7-benzylidene-1-nitro-1-desoxy-D-alpha-glucoheptitol formed. 37.7 g. (29%) of the crude product was obtained. The crude product was purified by recrystallizing once from water. The purified product showed a melting point of 161 to 163° C. $(\alpha)_D^{28}$ in water (concentration 2 g. per 100 ml. of solution) was -42.5°.

Example 11

114 g. of sodium 4,6-benzylidene-D-glucopyranose, 250 ml. of nitromethane and 2000 ml. of methanol were treated as in Example 5 except that the reaction temperature was 6 to 8° C. and the mixture was allowed to stand for 432 hours. The yield of 5,7-benzylidene-1-nitro-1-desoxy-D-alpha-glucoheptitol, after a single recrystallization from water, was 28 g.

Example 12

To 8.1 g. of 4,6-benzylidene-D-glucopyranose dissolved in about 100 ml. of methanol containing 25 ml. of nitromethane was added 1.4 g. of sodium, as sodium methoxide, in about 100 ml. of methanol and the entire mixture then made up to 250 ml. by the addition of methanol. As the reaction proceeded at room temperature, the specific optical rotation of this mixture, based on the benzylidene glucose, showed the following successive values

Elapsed Time	Specific Optical Rotation
Minutes	Degrees
6	-4.6
30	-13.0
60	-23.1
120	-27.1
230	-27.4

After 5 hours, the mixture was acidified with 4 ml. of glacial acetic acid. Upon concentration in the manner described in the previous examples there was obtained 2.04 g. of crude 5,7-benzylidene-1-nitro-1-desoxy-D-alpha-glucoheptitol.

Example 13

To 8.0 g. of 4,6-benzylidene-D-glucopyranose dissolved in about 100 ml. of commercial absolute ethanol containing 25 ml. of nitromethane was added 2.4 g. of potassium hydroxide dissolved in about 100 ml. of absolute ethanol, and the solution was then made up to 250 ml. by the addition of absolute ethanol. After the solution was allowed to stand for 5 hours at room temperature, it was acidified with 4 ml. of glacial acetic acid. Upon concentration in the manner described in the previous examples, there was obtained 1.3 g. of crude 5,7-benzylidene-1-nitro-1-desoxy-D-alpha-glucoheptitol. After recrystallization from water the product showed a melting point of 160 to 162° C. and $(\alpha)_D^{25}$ in water was -41°.

PREPARATION OF 1-NITRO-1-DESOXY-D-ALPHA-GLUCOHEPTITOL FROM 5,7-BENZYLIDENE-1-NITRO-1-DESOXY-D-ALPHA-GLUCOHEPTITOL

Example 14

A mixture of 5 g. of 5,7-benzylidene-1-nitro-1-desoxy-D-alpha-glucoheptitol, and 50 ml. of 0.1 N sulfuric acid was heated at 70 to 75° C. for 40 minutes and then at 100° C. for 15 minutes. After cooling, the mixture was extracted with ether to remove the liberated benzaldehyde. Barium carbonate was added to neutralize the sulfuric acid and the barium sulfate which precipitated was removed by filtration. The clear solution remaining was concentrated to dryness at reduced pressure. The residue thereby obtained was recrystallized from ethanol and there was obtained 2.8 g. (77%) of 1-nitro-1-desoxy-D-alpha-glucoheptitol which showed a melting point of 138 to 139° C. $(\alpha)_D^{23}$ in water (concentration 6.4 g. per 100 ml. of solution) was +3.1°.

The proof of the structure and the properties of 1-nitro-1-desoxy-D-alpha-glucoheptitol have been described by Sowden and Fischer (J. Am. Chem. Soc., 68, 1511 (1946)).

PREPARATION OF 5,7-BENZYLIDENE-2,6-ANHYDRO-1-NITRO-1-DESOXYHEPTITOL

Example 15

A mixture containing 126 g. of 4,6-benzylidene-D-glucopyranose, 250 ml. of nitromethane, 3160 ml. of methanol and 21.7 g. of sodium, as sodium methoxide, was allowed to stand for 24 hours at room temperature. Thereafter, the mixture was acidified with a slight excess of glacial acetic acid. Then the mixture was concentrated at reduced pressure until a sirupy residue was obtained. A small amount of crystalline material formed in the sirupy residue. Water was added thereto and the crystals removed by filtration. The crude crystals were dissolved in methanol and then precipitated from the methanol by the addition of water. The crystals obtained weighed 7.22 g. (5%) and were identified as 5,7-benzylidene-2,6-anhydro-1-nitro-1-desoxyheptitol. After another recrystallization from aqueous methanol, the crystals melted at 211 to 212° C. and $(\alpha)_D^{31}$ in methanol (concentration 1.3 g. per 100 ml. of solution) was -35.4°.

Example 16

The procedure of Example 15 was followed except that the mixture was allowed to stand 18 days at 6 to 8° C. before it was acidified. There was obtained 3% of 5,7-benzylidene-2,6-anhydro-1-nitro-1-desoxyheptitol. After separation of the aforementioned compound, the remaining liquor was treated in accordance with Examples 9, 10,

11, 12 and 13 and there was obtained 19% of 5,7-benzylidene-1-nitro-1-desoxy-D-alpha-glucosidetitol.

PREPARATION OF 2,6-ANHYDRO-1-NITRO-1-DESOXY-HEPTITOL

Example 17

A solution of 1.2 g. of 5,7-benzylidene-2,6-anhydro-1-nitro-1-desoxyheptitol in 10 ml. of 0.1 N sulfuric acid was heated at 100° C. for one hour. Thereafter, the mixture was treated to remove the liberated benzaldehyde and the sulfuric acid as described in Examples 8 and 14. There was obtained 0.66 g. (77%) of 2,6-anhydro-1-nitro-1-desoxyheptitol which showed a melting point of 177 to 177.5° C. and $(\alpha)_D^{22}$ in water (concentration 3.7 g. per 100 ml. of solution) was +8.2°.

The proof of the structure of 2,6-anhydro-1-nitro-1-desoxy-heptitol has been described by Sowden and Fischer in J. Am. Chem. Soc., 68, 1511 (1946).

PREPARATION OF 1-NITRO-1-DESOXY-D-ALPHA- AND BETA-GLUCOSIDETITOLS

Example 18

To 10 g. of powdered D-glucose suspended in a mixture of 100 ml. of methanol and 50 ml. of nitromethane was added 2 g. of sodium, as sodium methoxide, in 100 ml. of methanol. The mixture was shaken for 22 hours at room temperature and was then acidified by the addition thereto of 6 ml. of glacial acetic acid. Thereafter the solution was concentrated at reduced pressure, about 200 ml. of water was added, and the concentration at reduced pressure was continued until the volume of the solution was reduced to 100 ml. The solution was then passed through a column of an ion exchange resin (sold under the trade name of AMBERLITE-I.R.-100-H-A. G.) sufficient to remove the sodium ions present. The solution was then treated with a decolorizing carbon and was then concentrated at reduced pressure to a nearly colorless sirup. This sirup contained a mixture of 1-nitro-1-desoxy-D-alpha-glucosidetitol and 1-nitro-1-desoxy-D-beta-glucosidetitol and some unchanged D-glucose.

PREPARATION OF 1-METHYL-1-NITRO-1-DESOXY-L-SORBITOL AND 1-METHYL-1-NITRO-1-DESOXY-L-MANNITOL

Example 19

To a suspension of 5 g. of L-arabinose in a mixture of 30 ml. of methanol and 25 ml. of nitroethane was added 40 ml. of methanol containing 1.1 g. of sodium. The mixture was shaken at room temperature for 25 hours and a clear solution resulted. To this solution was added 200 ml. of ethyl ether (U. S. P. grade). The resulting amorphous precipitate was filtered and washed in succession with a mixture of equal volumes of methanol and ethyl ether, then with ethyl ether and finally with petroleum ether. The precipitate was dried in vacuo over phosphorus pentoxide. There was finally obtained 7.0 g. of a white hygroscopic powder consisting of the mixed sodium salts of the desired sugar C-nitroalcohols, e. g., 1-methyl-1-nitro-1-desoxy-L-sorbitol and 1-methyl-1-nitro-1-desoxy-L-mannitol. The amorphous salts contained 9.1% of sodium by analysis, (theory 9.3%).

When treated with nitrous acid the powder consisting of the above-mentioned sodium salts

showed the clear blue coloration of a pseudonitroso salt, demonstrating the presence of a secondary nitro group and, therefore, of the desired condensation products.

5 We claim:

1. 2,6-anhydro-1-nitro-1-desoxyheptitol.

2. The process of producing carbohydrate C-nitro-alcohol which comprises effecting chemical reaction between an aldose sugar and a nitroparaffin by contacting in intimate admixture said sugar and said nitroparaffin in the presence of an alkaline agent under substantially anhydrous conditions at a temperature not exceeding about 40° C. and recovering C-nitro-alcohol, 15 said nitroparaffin containing the group

3. The process which comprises effecting chemical reaction between an aldose sugar and 20 nitromethane by contacting in intimate admixture said sugar and said nitromethane in the presence of an alkaline agent under substantially anhydrous conditions at a temperature not exceeding about 40° C.

25 4. The process which comprises effecting chemical reaction between aldopentose and a nitroparaffin containing the group

30 by contacting in intimate admixture said aldopentose and said nitroparaffin in the presence of an alkaline agent under substantially anhydrous conditions at a temperature not exceeding about 40° C.

35 5. The process which comprises effecting chemical reaction between an aldohexose and a nitroparaffin containing the group

40 by contacting in intimate admixture said aldohexose and said nitroparaffin in the presence of an alkaline agent under substantially anhydrous conditions at a temperature not exceeding about 40° C.

45 6. The process which comprises effecting chemical reaction between a benzylidene substituted aldose sugar and a nitroparaffin containing the group

50 by contacting in intimate admixture said aldose sugar and said nitroparaffin in the presence of an alkaline agent under substantially anhydrous conditions at a temperature not exceeding about 40° C.

55 7. The process which comprises effecting chemical reaction between 4,6-benzylidene-D-glucopyranose and a nitroparaffin containing the group

60 by contacting in intimate admixture said 4,6-benzylidene-D-glucopyranose and said nitroparaffin in the presence of an alkaline agent under substantially anhydrous conditions at a temperature not exceeding 40° C.

65 8. The process which comprises effecting chemical reaction between 4,6-benzylidene-D-glucopyranose and nitromethane by contacting in intimate admixture said 4,6-benzylidene-D-glucopyranose and said nitromethane in the presence of potassium hydroxide under substantially anhydrous conditions at a temperature of about 22° C. to about 28° C.

9. The process which comprises effecting chemical reaction between xylose and nitromethane by contacting in intimate admixture said xylose and said nitromethane in the presence of sodium methoxide under substantially anhydrous conditions at a temperature of about 22° C. to about 28° C. and recovering the product resulting from said reaction. 5

10. The process which comprises effecting chemical reaction between glucose and nitromethane by contacting in intimate admixture said glucose and said nitromethane in the presence of sodium methoxide under substantially anhydrous conditions at a temperature of about 22° C. to about 28° C. and recovering the product resulting from said reaction. 10

11. The process which comprises effecting chemical reaction between 4,6-benzylidene-D-glucopyranose and nitromethane by contacting in intimate admixture said 4,6-benzylidene-D-glucopyranose and said nitromethane in the

presence of sodium methoxide under substantially anhydrous conditions at a temperature of about 22° C. to about 28° C., and thereafter treating the resultant 5,7-benzylidene 2,6-anhydro-1-nitro-1-desoxyheptitol with sulfuric acid at a temperature of about 100° C.
